CLAIM

The ornamental design for a particle sorting module mount, as shown and described.

DESCRIPTION

FIG. 1 is a top view of a particle sorting module mount; FIG. 2 is a front view of the particle sorting module mount; FIG. 3 is a first side perspective view of the particle sorting module mount; and, FIG. 4 is a second side perspective view of the particle sorting module mount.

The broken lines illustrate portions of the particle sorting module that form no part of the claimed design.
